SCARF

Lewis Barry, Upper Darby, Pa.

Application September 2, 1954, Serial No. 32,135

Term of patent 3½ years

(Cl. D3—12)

To all whom it may concern:

Be it known that I, Lewis Barry, a citizen of the United States, and a resident of Upper Darby, Delaware County, State of Pennsylvania, have invented a new, original, and ornamental Design for a Scarf, of which the following is a specification, reference being had to the accompanying drawing forming a part thereof, and showing a scarf embodying my new design.

I claim:

The ornamental design for a scarf, substantially as shown.
